UNITED STATES PATENT OFFICE

105,766

DESIGN FOR A CLOCK

Charles Hilaire Henri Rodanet, Neuilly-sur-Seine,
France, assignor to Société Anonyme; Etab-
lissemens Ed. Jaeger, Levallois-Perret, France

Application December 28, 1936, Serial No. 66,778
In France July 4, 1936

Term of patent 14 years

To all whom it may concern:

Be it known that I, Charles Hilaire Henri Rodanet, a citizen of the Republic of France, residing 23 Villa Madrid, Neuilly-sur-Seine (Seine), France, have invented a new, original, and ornamental Design for a Clock, of which the following is a specification, reference being had to the accompanying drawing, forming a part thereof.

In the drawing:

Fig. 1 is a front elevation of a clock showing my new design; and

Fig. 2 is a side elevation.

I claim:

The ornamental design for a clock as shown.

CHARLES HILAIRE HENRI RODANET.
